UNITED STATES PATENT OFFICE.

ALBERT WANNER, JR., OF HOBOKEN, NEW JERSEY.

DESIGN FOR A CHAIR-BACK.

SPECIFICATION forming part of Design No. 35,902, dated May 6, 1902.

Application filed March 20, 1902. Serial No. 99,216. Term of patent 14 years.

To all whom it may concern:

Be it known that I, ALBERT WANNER, Jr., a citizen of the United States, and a resident of Hoboken, in the county of Hudson and State of New Jersey, have invented and produced a new and original Design for a Chair-Back, of which the following is a full, clear, and exact description.

Reference is to be had to the accompanying drawings, forming a part of this specification, in which—

Figure 1 is an elevation of a chair-back, showing my design; and Fig. 2 is a plan view.

The design in its entirety consists of a marginal frame having the side portions a a' and a curved top portion a^2 , and within this marginal frame are the internal members b c . Said internal members meet each other at the lower portion of the chair-back to produce a stem d . The members b c diverge from this stem in upward and outward directions, and said members have the inwardly-curved portions e f , which touch the side and top portions of the marginal frame. These inwardly-curved portions e f of said members extend

downwardly from the top a^2 of the marginal frame. They are extended across one another in overlapping order, as shown at g g' , and the end portions of said members are then extended toward the upwardly-diverging portions of the same members, said end portions being curved into the terminal hooks h .

i is the chair-seat, and j j' are the side arms.

The leading feature of the design is the internal members within a marginal frame and 35 extended in upwardly-diverging relation from a stem and having inwardly-curved portions which overlap one another.

Having thus described my invention, I claim as new and desire to secure by Letters 40 Patent—

The design for a chair-back herein shown and described.

In testimony whereof I have signed my name to this specification in the presence of 45 two subscribing witnesses.

ALBERT WANNER, JR.
